UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ATTACHMENT-PLUG FITTING.

1,263,961.

Specification of Letters Patent. Patented Apr. 23, 1918.

Application filed April 20, 1916. Serial No. 92,471.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Attachment-Plug Fittings, of which the following is a specification.

My invention relates to attachment plug 10 fittings and the object of my invention is to provide means whereby a standard type of receptacle may be furnished with a barrier element which serves to convert the receptacle into a polarized fitting, should it be 15 desired to incorporate this feature therein.

Referring to the accompanying drawings,

Figure 1 is a perspective of the receptacle and plug in which my invention is embodied in one form;

20 Fig. 2 is an inverted plan of the plug element;

Fig. 3 is a detached perspective of one of the receptacle terminals and the polarizing element associated therewith;

25 Fig. 4 is a plan of the receptacle with the face plate and plug removed;

Fig. 5 is a section on the line 5—5, Fig. 4.

Fig. 6 is a perspective of a receptacle and plug of heavier capacity in which my invention 30 is embodied in different form;

Fig. 7 is a plan of this receptacle with face plate removed;

Fig. 8 is an inverted plan of the plug element; and

35 Fig. 9 is a longitudinal section on the line 9—9, Fig. 7, showing the plug inserted but partially broken away to disclose the barrier.

In many installations of attachment plug 40 fittings it is immaterial whether or not the engaging contacts of the plug and receptacle be polarized. On the other hand, there are frequently occasions in which it is desirable that the plug and receptacle should 45 be polarized so that the current shall always pass in the same direction through the implement energized by the current. I am aware that means have been heretofore provided by which such polarization has been 50 accomplished, but so far as I am aware such means have been permanently associated with the parts and form an integral or fixed part of the appliance and are such that neither element of the fitting can be employed 55 as a non-polarized device. The pres-

ent invention provides a barrier which may be installed in a standard non-polarized receptacle to polarize the same.

In the construction shown in Figs. 1 to 5, the present device comprises a receptacle 10 of the type shown in the Goodridge Patent 1,166,349 having a cup-shaped insulating body normally protected by a cover plate 11 with doors 12 opening to the receptacle chamber, and being secured to the face plate 65 by means of supporting ears 13 into which take countersunk securing screws 14 passing through the cover plate 11. The wire terminal straps 15 extend from diagonally opposite corners of the receptacle chamber 70 to the studs 16 which project upwardly through the insulating lining 17 and co-operate with the contacts 18 carried by the plug 19. In the form shown in the Goodridge patent these contacts 18 are so arranged with 75 relation to the stud 16 that they engage the same whether the plug is reversed in position or not. In other words, the fitting is not polarized.

I have now provided a barrier 20 in the 80 form of an angled strap, the base of which underlies one of the studs 16 and is held in position by means of the securing screw 21. The latter passes up through the bottom of the receptacle body the strap 15, base of the 85 barrier and threads into the tapped bore of the stud 16, so that the base of the barrier is clamped between the strap 15 and the stud 16. To receive this barrier and permit the full insertion of the plug 19, I provide a 90 channel 200 on one side of the entering end of the plug. It is obvious that when the plug is inserted in such position that the barrier 20 and channel 200 register, the plug may be inserted, whereas when the plug is 95 reversed, the barrier 20 engages the body of the plug on the opposite side and prevents its entry into the receptacle.

In the form shown in Figs. 6 to 9 a receptacle of the same general construction, but 100 of larger capacity, is shown. In this form the barrier comprises a supplemental block of insulation 22 which is secured in position between the receptacle studs 16 by means of a securing screw 23 passing through the base. 105 The attachment plug 24 has a recess 25 formed in its entering end which receives the barrier 22 when the plug is inserted in one position. It is obvious, however, from Fig. 9 that if the plug be reversed in position the barrier 110

will engage the end of the plug and prevent its entry into the receptacle a sufficient distance to establish contact between the terminals of the plug and those of the receptacle.

- The constructions described both permit the standard non-polarized receptacles to be rendered polarized by the mere addition of the independent barrier elements 20 or 22.
- 10 The coöperating attachment plugs 19 and 24 are always provided with their recesses 200 or 25 since this in no way interferes with their utility when the receptacle is non-polarized and renders them fit for coöperation with the barriers if the receptacle has been converted into a polarized fitting by the addition of the barrier element.

Various other ways of accomplishing the same result will readily occur to those skilled 20 in the art which do not depart from what I claim as my invention.

I claim as my invention:—

1. An attachment plug receptacle having an insulating body and receptacle terminals 25 mounted thereon, in combination with an independent barrier element and means for detachably securing the same within the receptacle to polarize the same, said barrier being arranged in position to prevent non-polarized engagement of the coöperating contacts on the plug and receptacle, respectively.
2. An attachment plug receptacle having an insulating body and receptacle terminals 35 mounted thereon, in combination with an independent barrier element and means for detachably securing the same within the receptacle to polarize the same, together with an attachment plug having a channel adapt- 40 ed to receive said barrier when the plug is

inserted in predetermined polarized relation to the terminals of the receptacle.

3. An attachment plug receptacle having a chambered, insulating body, wire terminals mounted at opposite ends of the receptacle, plug-receiving terminals within the chamber and straps extending thereto from the wire terminals, an insulating lining overlying said straps and extending upward beyond the wire terminals to guard against the entry of wire beards into the chamber, and an independent barrier element mounted on the base of the chamber and passing upward through said lining into the path of an entering plug, and adapted to prevent the insertion of the latter save in polarized relation to the terminals of the receptacle.

4. An attachment plug receptacle having a chambered insulating body, receptacle terminals upstanding from the base of the chamber together with a readily detachable barrier upstanding from said base and projecting into the path of a non-polarized plug to prevent the engagement of its terminals with those of the receptacle.

5. An attachment plug receptacle having an insulating body, receptacle terminals mounted therein and adapted to coöperate with the contacts of a non-polarized plug, in combination with a barrier device and means for optionally securing the same in the receptacle to polarize the same.

In testimony whereof I have signed my name to this specification, in the presence of two subscribing witnesses.

GEORGE B. THOMAS.
